CLAIM

The ornamental design for a bed connector, as shown and described.

DESCRIPTION

FIG. 1 is a front, right and top perspective view of a bed connector showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top view thereof;

FIG. 8 is a bottom view thereof; and,

FIG. 9 is a perspective view thereof, shown in an environment of use; and,

FIG. 10 is another perspective view thereof, with the bed connector shown in a detached position, in its environment of use.

The broken lines in FIGS. 9 and 10 illustrating a bed frame, depict environmental subject matter that forms no part of the claimed design. The remaining broken lines depict portions of the bed connector and form no part of the claimed design.

1 Claim, 10 Drawing Sheets
